AIR CLEANER

Caleb E. Summers, Pontiac, Mich., assignor to
General Motors Corporation, Detroit, Mich., a
corporation of Delaware

Application October 31, 1927. Serial No. 229,995

3 Claims. (Cl. 183—110)

This invention relates to air cleaners and particularly to an air cleaner for use on the air intake of a carburetor of an internal combustion engine.

It is an object of the invention to provide an air cleaner which is simple in construction, efficient in operation, and which offers practically no resistance to the passage of a current of air therethrough.

It is another object of the invention to provide an air cleaner so mounted that the air which enters the cleaner is first caused to travel over the outside thereof and so shaped that the current of air passing thereover is given such a motion that the dirt carried thereby is separated therefrom before the air enters the interior of the cleaner.

More specifically, it is an object of the invention to provide an air cleaner connected to the air intake of the carburetor of an internal combustion engine and mounted in the path of the current of air produced by the engine fan so that the air which enters the interior of the cleaner must first pass over its exterior which is so shaped that the current of air passing thereover is given such a motion that the dirt carried thereby is separated from the air before the latter enters the interior of the cleaner.

It is another object of the invention to provide an air cleaner including an open ended body member which is greater in diameter at one end than the other and has inclined side walls between its ends, and, more specifically, to provide an air cleaner such as described above which is provided with a baffle plate over and spaced from its larger or intake end.

It is another object of the invention to provide an air cleaner including a substantially bell-shaped body member which is open at its opposite ends, and, more specifically, to provide an air cleaner such as described above which is provided with a baffle plate over and spaced from its larger or intake end.

Other objects of the invention will appear in the course of the following description of the preferred embodiment of my invention which is shown in the accompanying drawing.

In the drawing—

Fig. 1 is a side elevation of my air cleaner installed on the air intake conduit of the carburetor of an internal combustion engine;

Fig. 2 is an intake end elevation of my air cleaner; and

Fig. 3 is a section on the line 3—3 of Fig. 2.

Referring to the drawing, the reference character 5 indicates an internal combustion engine on the front end of which is mounted the usual fan 6 which when the engine is running forces

a current of air rearwardly about the engine. At 7 is shown the intake manifold which opens into the intake ports in the side of the engine block and which is provided with the usual riser 8 to which the carburetor 9 is connected. The carburetor is preferably of the type in which the air intake 10 opens toward the rear of the engine, as shown in the drawing.

My air cleaner, which is designated generally by the reference character 11, includes a body member 12, which is frusto-conoidal, or, more specifically, substantially bell-shaped as shown in the drawing. It is preferable to make the flared end portion 13 of the body member of the shape of the surface generated by revolving the arc of a circle about an axis parallel with the plane of said circle and outside of the circumference thereof. Preferably, and as shown in the drawing, the flared-out portion merges at its smaller end tangentially into a cylindrical portion 14 and extends in the opposite direction to the point at which a tangent to its surface makes an angle of 60° with the axis of the cylindrical portion.

A baffle plate 15, smaller in diameter than the greatest diameter of the body member, is secured to and spaced therefrom by the legs 16 which extend into the flared-out portion and are secured thereto in any suitable manner. The legs 16 are preferably made of such length that the baffle plate is spaced from the body member a sufficient distance to provide an air inlet opening 17 between the body and the plate of at least twice the area of the air intake opening in the carburetor.

As shown in Fig. 1, the air cleaner is mounted on the carburetor with its cylindrical portion in the mouth of the air intake thereof and secured thereto in any desired manner. The larger of air intake end of the cleaner, it will be noted, is pointed toward the rear of the engine and the longitudinal axis of the cleaner is substantially parallel with that of the engine.

When the engine starts, the fan 6 forces a current of air rearwardly over the engine and at the same time air is drawn into the engine cylinders through the air inlet opening 17 and the carburetor. The portion of the current of air generated by the fan which strikes the outwardly curved sides of the air cleaner 11 is deflected more and more from the direction of the axis of the cleaner as it travels from front to rear thereof, as indicated by the arrows in Fig. 1. Any dust particles carried by the air are thus given a motion in a direction which carries them away from the air inlet opening 17. The air in-

let opening 17 is of such size that the velocity of the air current drawn therethrough is insufficient to overcome the velocity which the curved sides of the cleaner give the dust particles in a direction away from the inlet opening so that the dust particles with a portion of the air current pass by the inlet opening, as indicated by the arrows at the extreme left in Fig. 1. The strength of the suction is, however, sufficient to draw a portion of the air from the current inwardly, as indicated by the arrows, where after impinging against the baffle plate 15 it enters the cleaner through the inlet opening 17, the baffle plate preventing any dust which remains in the air from entering the cleaner therewith.

It is apparent that I have provided an air cleaner of very simple construction, which offers practically no resistance to air currents passing therethrough and is efficient in removing solid impurities from the air. It is obvious that my cleaner may be installed on an engine having a carburetor whose air intake does not open toward the rear by providing a curved conduit which opens at one end into the air intake of the carburetor and at its other end, to which the air cleaner is to be connected, toward the rear of the engine.

My air cleaner is not restricted to use with the carburetor of an internal combustion engine, but may be used wherever air is to be drawn from a moving current of air. To operate prop-

erly the cleaner should be positioned, in all cases, so that its air intake end faces in the direction toward which the current of air is traveling.

I claim:

1. In an air cleaner, a body member which is open at its opposite ends and which is of greater diameter at its intake end than at its discharge end and which has inclined sides between its ends, and a baffle plate over the opening in the larger end of the body member and spaced therefrom. 80 85

2. In an air cleaner, a body member which is open at its opposite ends and which is of greater diameter at its intake end than at its discharge end and whose sides from adjacent the smaller end diverge at an increasing rate from the longitudinal axis of the body member, and a baffle plate over the opening in the larger end of the body member and spaced therefrom. 90

3. In an air cleaner, a body member which is open at its opposite ends and which is of greater diameter at its intake end than at its discharge end and which has inclined sides between its ends, a baffle plate over the opening in the larger end of the body member, and means securing the baffle plate to the body member and spacing it therefrom so as to leave a substantially annular air intake opening between the baffle plate and the body member. 95 100
